US00D826970S

(12) **United States Design Patent** (10) **Patent No.:** **US D826,970 S**
(45) **Date of Patent:** **** Aug. 28, 2018**

(54) **DISPLAY SCREEN OR PORTION THEREOF
WITH GRAPHICAL USER INTERFACE**

(71) Applicant: **SAP SE**, Walldorf (DE)

(72) Inventors: **Emil Voutta**, Heidelberg (DE); **Florian Jann**, Heidelberg (DE); **Michael Krenkler**, Wiesloch (DE); **Marc Ziegler**, Mauer (DE)

(73) Assignee: **SAP SE**, Walldorf (DE)

(**) Term: **15 Years**

(21) Appl. No.: **29/599,918**

(22) Filed: **Apr. 7, 2017**

Related U.S. Application Data

(62) Division of application No. 29/539,995, filed on Sep. 18, 2015, now Pat. No. Des. 783,651.

(51) **LOC (11) Cl.** **14-04**

(52) **U.S. Cl.**

USPC **D14/486**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The outermost broken lines in the FIGURE show a display screen or portion thereof, and form no part of the claimed design.
